(57) **CLAIM**

The ornamental design for set of connectors for a modular cable protector, as shown and described.

DESCRIPTION

FIG. 1 is a perspective view of a set of connectors for a modular cable protector showing my new design.

FIG. 2 is a top plan view thereof.

FIG. 3 is a right side elevational view thereof, with the left side elevational view being a mirror image of FIG. 3.

FIG. 4 is a bottom plan view thereof.

FIG. 5 is front elevational view thereof; and,

FIG. 6 is a rear elevational view thereof.

The broken line showing is included for the purpose of illustrating environmental features and forms no part of the claimed design.

1 Claim, 3 Drawing Sheets
